UNITED STATES PATENT OFFICE.

JAMES E. MACWILLIAM, OF HUBBARDSTON, MASSACHUSETTS.

FIRE-EXTINGUISHER.

SPECIFICATION forming part of Letters Patent No. 739,016, dated September 15, 1903.

Application filed July 30, 1902. Serial No. 117,599. (No model.)

To all whom it may concern:

Be it known that I, JAMES E. MACWILLIAM, a citizen of the United States, residing at Hubbardston, in the county of Worcester and 5 State of Massachusetts, have invented a new and useful Fire-Extinguisher, of which the following is a specification.

This invention relates to that class of sprinkling systems which are employed for protection against fire.

The especial objects of this invention are to provide a simple, efficient, and reliable automatic sprinkling system which will discharge a limited volume of water with the 15 best possible efficiency and which will then cease to operate, so that heavy water losses resulting from the sprinkling system running longer than necessary will be avoided.

To these ends this invention consists of the 20 automatic sprinkling system and of the combinations of parts therewith, as herein-after described, and more particularly pointed out in the claims at the end of this specification.

25 In the accompanying drawings, Figure 1 is a perspective view showing the application of a sprinkling system constructed according to my invention to a compartment. Fig. 2 is a side view, partially broken away, of the supply-tank. Fig. 3 is a fragmentary sectional view thereof, showing the parts in a different relative position; and Fig. 4 is a detail view illustrating a construction for turning in an alarm in connection with the sprinkling system.

30 The use of automatic sprinklers which are usually supplied with water from the ordinary city or town water-service has now become a well-recognized means for protection 40 against fire.

The use of the ordinary automatic sprinkling systems is open to one serious objection—that is to say, when the sprinkling system has been once started into operation the 45 water will continue to run until the main supply is shut off. On this account it frequently happens that when a sprinkling system is started into operation either from defects in the appliances or from comparatively small

fires the water will continue to run for comparatively long periods of time, resulting in heavy losses from water damage. In fact, in nearly all cases where sprinkling systems are employed for extinguishing fire it has been found that the water damage nearly equals 55 or exceeds the actual fire losses.

In practice I have found that an automatic sprinkling system gives its greatest protection at the inception or very commencement of a fire and that if a sprinkling system is not 60 sufficiently powerful or does not operate efficiently enough to extinguish a fire almost as soon as it is kindled it is useless to allow the water to continue to run out through the sprinkler-heads.

To overcome the objections of the ordinary automatic sprinkling systems which are supplied from city or town water-services, I propose to provide a sprinkling system in which the automatic sprinkler-heads are supplied 70 from tanks or reservoirs, so that when the sprinkling system is called into action and the tank emptied the operation of the system will cease and further unnecessary loss will be avoided.

A still further object of my invention is to provide an automatic sprinkling system in which a comparatively low pressure will be maintained at all times, but which is provided with means for promptly increasing 80 said pressure when the sprinkling apparatus is called into operation. For example, in a sprinkling system constructed according to my invention a normal pressure of one or two atmospheres will be maintained for forcing 85 the water from the tank up through the sprinklers, while when the sprinklers start in operation, so as to lower the level of water in the tank, the pressure will be at once raised therein, so that the water will be forced out 90 through the sprinkler-heads with such heavy pressure as to insure an efficient fire-extinguishing effect. To provide for this increase of normal pressure when the system commences to operate, I preferably provide means 95 for chemicalizing the contents of the tank, which means are preferably controlled by the level of the water.

- Referring to the accompanying drawings for a detailed description of a sprinkling system constructed according to my invention, as illustrated in Fig. 1, A designates a tank or reservoir. In practice the tank or reservoir is preferably formed of metal and is provided with a stand or base, so that the same may be placed in one corner of the compartment or room to be protected. If preferred, the tank can be incased, although in practice I prefer to have the tank kept in plain sight, so that it is at all times open to inspection and the amount of pressure maintained therein can be readily read.
- 15 Leading from the bottom of the tank A is an outlet-pipe B, which extends up and is provided with branch pipes for supplying the ordinary sprinkler-heads C. The sprinkler-heads C may be arranged or grouped together in any desired manner, the arrangement illustrated in Fig. 1 being shown simply for the purpose of illustration.
- 20 The upper end of the tank A, as shown most clearly in Fig. 3, is closed by having a cover 10 threaded thereon. The cover 10 is provided with a handle or rail 11. Opening through the cover 10 is a pressure-pipe 12, which is provided with a gage 13 and an air-valve 14, through which air may be pumped to maintain the normal pressure in the tank. In practice the air-valve 14 may be soldered up or sealed after the pressure is raised to the requisite point in the tank, so that after the system has been once installed a constant pressure may be maintained therein.
- 25 As shown most clearly in Fig. 2, the tank A is partially filled with liquid. I preferably employ water having a sufficient amount of carbonates dissolved therein so that when acid is mixed with the solution it will generate a comparatively heavy pressure. To provide for automatically supplying acid to the solution when the system starts into operation, the tank may be provided with lugs 15, as shown in Fig. 3, and journaled in the lugs 15 is a cross-bar 16, having an acid bottle or receptacle 17. The center of gravity of the acid-bottle 17 is low enough to normally hold the bottle in an upright position, as illustrated in Fig. 2. Secured to one side of the bottle 17 is a chain 18, which connects to a float 19. Fitting loosely into the mouth of the acid-bottle 17 is a cover 20. By means of this construction a comparatively small normal pressure may be maintained in the system. When any of the sprinklers start into operation, however, the level of water in the tank will be lowered, the acid-bottle will be inverted, as illustrated in Fig. 3, and the pressure in the tank will be promptly raised, so that the water will be sprayed or forced out through the sprinkler-heads with such force as to insure the sprinklers acting with the greatest possible efficiency.
- 30 65 If desired, several compartments may be

protected from a single supply-tank, although in practice I prefer to provide a supply-tank for each compartment, so that an independent system will be maintained in each room or compartment which is protected according to my invention. In the use of this system, furthermore, the water damage will be reduced to a minimum, because when the tank has been emptied the system ceases to operate.

70 In connection with a system constructed according to my invention I may employ any of the ordinary devices for turning in an alarm when the system starts into operation. For example, as shown in Fig. 4, the fusible section 21 of each of the sprinkler-heads may be connected to hold up a contact-piece 22, which will be released and close a circuit to sound a bell D and operate an annunciator or other signal in the ordinary manner.

75 I am aware that numerous changes may be made in practicing my invention by those who are skilled in the art without departing from the scope thereof as expressed in the claims. I do not wish, therefore, to be limited to the construction I have herein shown and described; but

80 What I do claim, and desire to secure by Letters Patent of the United States, is—

1. In a fire-extinguishing apparatus, the combination of a supply-tank with air-pressure maintained therein to force water from said tank as soon as an outlet therefrom is opened, and means controlled by the escape of water from said tank for increasing the pressure therein.

force solution through the sprinklers as soon as opened, an acid bottle or receptacle mounted in said tank, and a float controlled by the escape of the solution from the tank for inverting the acid-bottle to thereby increase the pressure in the tank when the sprinklers start in operation.

In testimony whereof I have hereunto set my hand in the presence of two subscribing witnesses.

JAMES E. MACWILLIAM.

Witnesses:

PHILIP W. SOUTHGATE,
HENRY E. HILL.
